UNITED STATES PATENT OFFICE.

WILLIAM M. KELLY, OF JERSEY CITY, NEW JERSEY.

PRINTING-PRESS-BED MOVEMENT.

Application filed April 23, 1921. Serial No. 463,932.

To all whom it may concern:

Be it known that I, WILLIAM M. KELLY, a citizen of the United States, and residing at Jersey City, Hudson County, New Jersey, have invented certain new and useful Improvements in Printing-Press-Bed Movements, (for which I have filed applications in Great Britain, Jan. 2, 1918, No. 120,823; France, Jan. 10, 1918, Patent No. 494,886; Canada, Dec. 14, 1917, Patent No. 201,448; Germany, June 19, 1919, No. 31,915; and Japan, Jan. 31, 1918, Patent No. 35,567), of which the following is a specification.

This invention relates to mechanical movements and more particularly to a mechanism for reciprocating the bed of a printing press.

The salient objects of the invention are to provide a simple and positive means for reciprocating the bed of the press at a uniform velocity during the greater portion of its stroke and to give an easy and smooth reversal at the end portions of the reciprocation. For these purposes the mechanism comprises in combination with the reciprocating member a second reciprocating member driven in timed relation with the first member, to make a plurality of reciprocations while the first member makes a single reciprocation and means for connecting the two members when the second member is making one of its reversals whereby the first member is quickly reversed. Other objects and features of the invention will be apparent from the description taken in connection with the drawings, in which,

Fig. 1 is a side elevation of a portion of a printing press having the structure of the invention embodied therein;

Fig. 2 is a sectional elevation taken substantially on the line 2—2 of Figure 3;

Fig. 3 is a sectional view in plan, showing the parts illustrated in Figures 1 and 2;

Figs. 4 to 9 inclusive are diagrammatic views showing the relative positions of the parts when the bed is being reversed. In these views the driving gears have been shown as separated laterally in order to clearly illustrate their relative angular positions.

In the embodiment of the invention illustrated in the drawings, the reciprocating member or bed 10 is mounted to slide on four parallel roller bearings 11, which in turn are supported by the frame 12 of the press. Centrally located on the bottom of

the bed and extending lengthwise thereof are two spaced racks 13 and 14, through which the bed is adapted to be driven at a uniform velocity first in one direction and then in an opposite direction. For this purpose a shaft 15 is mounted in the frame and is adapted to be driven by a pulley 16, or any other desired means. Secured to rotate with this shaft is a pinion 17, which meshes with a large spur gear 18, loosely mounted on the shaft 19. Compounded with this gear 18, or secured to rotate in unison therewith is a wheel 20, which is arranged in the plane of the rack 14, and has a portion of its periphery provided with gear teeth 21, and the remaining portion being blank as shown at 22. As clearly illustrated in the diagrammatic views, the teeth 21 extend around a portion of the circumference which subtends an angle of approximately 120°. Interposed between the wheel 20 and the rack 14 is a pinion 23, which is secured to a short shaft 24 mounted in bearings 25 and 26, carried by the frame. As the wheel 20 rotates the teeth 21 thereon will mesh with the teeth on the gear 23 and thus through the rack 14 drive the bed 10 at a uniform velocity in one direction. The bed is driven in the opposite direction by a similar mechanism which will now be described. The shaft 15 extends laterally outside of the frame and carries a gear 27, which meshes with an easy gear 28 secured to the shaft 29, also mounted in bearings on the frame. Attached to this shaft 29 to rotate therewith is a pinion 30 of the same size as the pinion 17, and which meshes with a gear wheel 31 of the same size as the gear wheel 18. Compounded with this gear 31, or adapted to rotate in unison therewith, is a wheel 32, which is similar to the wheel 20, and is formed with teeth 33, which extend around a portion of the circumference of the wheel, the remaining portion of the periphery being smooth or blank. As in the wheel 20, the teeth 33 subtend an angle of approximately 120°. Arranged in the plane of the wheel 32 and the rack 13 is a pinion 34, which is the same size as the pinion 23, and is also secured to the short shaft 24. As the wheel 32 rotates, the teeth 33 thereof will mesh with the teeth on the pinion 34, and thus drive the bed or reciprocating member. However, as the wheel 32 is rotated in an opposite direction relative to the wheel 20, the bed, when driven by the wheel 32, will be moved in a direction opposite to that

which it is driven when actuated by the wheel 20.

For the purpose of reversing the bed or reciprocating member at the ends of its stroke, a second reciprocating member is provided which is adapted to be periodically connected with the first reciprocating member when the former is making a reversal. As shown in the drawings, this second reciprocating member may comprise a vertically arranged plate 35, which is located in the space between the wheels 20 and 32. The plate is mounted for its reciprocating movement on two blocks 36 and 37, which are carried by the frame and formed with guide-ways 38 and 39, respectively, the plate having slots 40 and 41, in which the blocks 36 and 37 are fitted. Adjacent the ends of the upper edge of the plate 35 are the short racks 42 and 43, which at the proper times are adapted to be alternately connected with the bed of the press so that the two reciprocating members are connected for movement in unison. The rack 42 is carried by an arm 44, which is pivoted at 45, and has a laterally extending pin 46, which works in a cam groove 47 formed in the cam block 48 carried by the frame of the press. In a similar manner the rack 43 is carried by an arm 49 pivoted at 50, and has a laterally extending pin 51, which works in a cam groove 52, formed in the cam block 53 carried by the frame of the press. Located between the racks 13 and 14 on the bottom of the bed are two rack blocks 54 and 55, the block 54 being positioned so that at the proper time it may be engaged by the rack 42 and the rack block 55 being positioned so that it may be engaged by the rack 43 when the press is being reversed at the right end of its stroke, as viewed in Figure 1.

For the purpose of reciprocating the plate 35, a shaft 56 is mounted in bearings in the frame and is rotated from the gear 27 by means of the gears 57 and 58, the latter gear being secured to the shaft 56 and being as shown in the drawings, of the same diameter as the gears 23 and 34 and of one-third the diameter of gears 18 and 20. Adjacent the plate 35, the shaft 56 has attached thereto a crank arm 59, which at its outer end carries a block 60, which is slidingly fitted in the groove 61 formed in the plate. Thus as the shaft 56 rotates a simple harmonic reciprocation will be given to the plate 35 through the crank and block connection. The axis of the block 60 which is pivoted to the crank arm describes a circle, the diameter of which is the same as the diameter of the pitch circles of the gears 58, 23 and 34. Because of these dimensions of the parts, it will be observed that when the crank 59 is in either its upper or lower vertical position that the velocity of the plate 35 and of the

bed 10, will be the same. Hence, if these two reciprocating members are connected together at these particular positions of the rotating crank 59, there will be no binding or straining of the parts.

In order to clearly describe the timing of the mechanism, reference will now be made to the diagrammatic views 4 to 9 inclusive. In Figure 1, the bed or reciprocating member 10 is shown substantially in its central position. In the diagrammatic view of Figure 4, the bed is shown approaching the right hand end of its stroke. In this figure and the other diagrammatic views it will be noted that the gears 20 and 23 have been shown as offset laterally with respect to the gears 32 and 34, this being necessary in order to show the relative positions of the toothed portions of the wheels 20 and 32. In Figure 4, the toothed portion of the wheel 20 has been driving the bed 10 in the direction indicated by the arrow, but it will be observed that the end of the toothed portion 21 will soon go out of mesh with the gear 23 and that this wheel 20 will therefore continue to drive the bed during a very small angle of its rotation. An inspection of the position of the crank 59 shows that it is a very slight angle in advance of its upper vertical position. Consequently, the velocity of the reciprocating plate 35 is approximately the same as that of the bed 10. Hence, it is possible to connect the two reciprocating members at this instant and for the small remaining driving angle of the wheel 20, the driving means of both the bed and plate will be effective. The cam block 53 is therefore located on the frame, and its groove 52 so formed that the rack 43 will be projected upwardly to engage the cooperating rack block 55 on the bottom of the bed when the crank 59 and wheel 20 are in the positions illustrated in this Figure 4.

The parts of the mechanism will continue to rotate in the directions indicated by the arrows, and an instant later will be in the positions illustrated in Figure 5. It will be observed that the blank portion of the wheel 20 is now opposite the pinion 23, and consequently that the bed is no longer driven by means of the wheel 20, the crank 59 having taken up this function. Thus as the plate 35 is retarded to zero velocity, the bed 10 will also be retarded, the positions of the parts when the two reciprocating members 10 and 35 are at the point of reversal and zero velocity being shown in Figure 6. From the positions illustrated in this figure, the parts move to positions shown in Figure 7. The toothed portion of the wheel 32 is just coming into mesh with the pinion 34 and the crank 59 is a slight angle in advance of its lower vertical position. Thus the velocity imparted to the two reciprocating members by their respective driving means are sub-

stantially the same, and hence the driving of the bed may be transferred from the crank 59 to the gear 32. While the crank is moving from the position shown in Figure 7 to that shown in Figure 8, both of the driving means are acting, the cam groove 52 causing the rack 43 to be entirely disengaged from the bed when the crank is in the position shown in Figure 8. The toothed portion of the wheel 32 will now operate to drive the bed at a uniform velocity for approximately one rotation of the pinion 34. During this time as the pinion 34 and crank 59 rotate at the same angular velocity, the crank 59 will also have made substantially one revolution. The positions of the parts at the time when the pinion 34 and the crank 59 have made substantially one revolution, are illustrated in Figure 9. As the velocities of the two reciprocating members 35 and 10 are substantially the same, the plate 35 may be connected to the bed at this instant, and the cam groove 47 is formed so that the rack 42 will be actuated into engagement with the co-operating rack block 54 on the bottom of the bed 10. The operation of the reversing means at this end of the stroke of the bed is similar to that at the other and requires no further description.

It is thus apparent that this invention comprises means for moving a reciprocating member at a uniform velocity first in one direction and then in the opposite direction, and a reversing means for the said reciprocating member, which consists of a second reciprocating member which makes a plurality of reciprocations for each reciprocation of the first member. With the proportions of the parts as described above, the plate 35 or second reciprocating member makes three complete reciprocations, while the bed or first reciprocating member makes one complete reciprocation. Thus if we designate the radius of the crank pin circle as r the bed will move at a uniform velocity a distance of $2r$, this being the circumference of the pitch circle of the pinion 58, then while the velocity of the bed is being retarded to zero, it will move through a distance equal to r . Likewise, when the velocity of the bed is being accelerated from zero, it will move through a distance r . Thus the distance that the bed moves through in travelling from one end of its stroke to the other may be represented by $2r+2r$. Thus when the second reciprocating member makes three complete reciprocations for one reciprocation of the bed or first reciprocating member, the bed will have a uniform velocity for about 75% of its travel, and with the reversing mechanism above described, will be successively retarded and accelerated with a harmonic motion at the ends of its stroke.

The invention has been shown in a press

of the two-revolution type. The impression cylinder 62 may be driven by a gear 63 which meshes with the gear 57. Furthermore, the bed may be provided with a cushioning means 64 of any desired type which is for the purpose of aiding in the retarding of the momentum of the bed at the ends of its stroke.

It will be observed that the arrangement of the bed driving means is such that there is no twist or side thrust given to the bed. The pinions 23 and 34 are secured to the same shaft, and are located symmetrically relatively to the center line of the bed. Hence, whether pinion 23 or 24 is driven, both gears will act on the racks 13 and 14, thereby centralizing the driving force.

Although a specific embodiment of the invention has been described and illustrated, it is apparent that the details thereof may be varied considerably without departure from the spirit of the invention.

Having thus described the invention what is claimed as new and desired to be secured by Letters Patent is:

1. The combination with a reciprocating member and means for reciprocating the same including two racks on said member, a pair of oppositely rotating gears each having teeth on a portion only of its periphery, a pinion interposed between each gear and one of the racks and constantly in mesh with said rack, the toothed portion of the gears being arranged so that the member is driven alternately in opposite directions, of a reversing mechanism including a second member which is reciprocated parallel to the first reciprocating member, and movable racks constituting means for directly connecting the two members while the second member is reversing.

2. In combination a frame having parallel ways, a member slidably mounted on said ways, and guiding or drive mechanism for reciprocating said member without any twist or side thrust including a rack on each side of the longitudinal centre line of the member, said racks being spaced equally from said centre line, a pinion engaging each rack, a pair of oppositely rotating gears each having teeth on a portion only of its periphery and constituting means for periodically driving said pinions with equal circumferential velocities first in one direction and then in the other, a second member which is reciprocated parallel to the first reciprocating member and has a shorter stroke than the first member, and devices comprising movable racks for connecting said second member to the first member along the centre line of the latter alternately at each end of the same to reverse the movement of said first member.

3. The combination with a reciprocating member and means for reciprocating the

- same including a pinion constantly in mesh with a rack on said member and adapted to drive the same in one direction, a second pinion constantly in mesh with a second rack on said member and adapted to drive the same in the opposite direction, and a pair of oppositely rotating gears each having teeth on a portion only of its periphery and constituting means for alternately connecting said pinions with a source of power, of a reversing mechanism including a second member which is reciprocated parallel to the first reciprocating member, one of said members having racks adapted to be moved into engagement with the other member to connect them for movement together when the second member is reversing, and means for automatically operating the movable racks so as to connect the two members substantially when one pinion is disconnected from the source of power.
4. The combination with a reciprocating member and means for reciprocating the same including a pair of parallel racks on said member, a shaft having two pinions secured thereto, each pinion being constantly in mesh with one of the racks, two oppositely rotating gears each having teeth on a portion only of its periphery adapted to drive one of the pinions, the said toothed portions of the gears being arranged so that the member is periodically driven alternately in opposite directions, of a reversing mechanism including a second member which is reciprocated parallel to the first reciprocating member, a second shaft having a crank operative to reciprocate said second member, the radius of the crank being the same as the radius of said pinions, means for driving said crank at the same angular velocity as said pinions and means for connecting the two members along the centre line of the first member during a reversal of the second member.
5. The combination with a reciprocating member and means for reciprocating the same including a gear constantly in mesh with said member and means for periodically connecting said gear with a source of power, of a reversing mechanism including a second reciprocating member moving in a path parallel to that of the first reciprocating member, one of said members having means adapted to be moved relative thereto

into engagement with the other member to connect them for movement together when the second member is reversing and a stationary cam for automatically operating said last mentioned means to move the latter to connect the two members substantially when the gear is disconnected from the source of power.

6. The combination with a reciprocating member and means for reciprocating the same including a gear constantly in mesh with said member and adapted to drive the same in one direction, a second gear constantly in mesh with said member and adapted to drive the same in the opposite direction, and means for alternately connecting said gears with a source of power, of a reversing mechanism including a second reciprocating member moving in a path parallel to that of the first reciprocating member, one of said members having means adapted to be moved relative thereto into engagement with the other member to connect them for movement together when the second member is reversing, and stationary cams for automatically operating said last mentioned means to move the latter to connect the two members substantially when one gear is disconnected from the source of power and to disconnect the two members substantially when the other gear is connected with the source of power.

7. The combination with a reciprocating member and means for reciprocating the same including two coaxial gears constantly rotating in opposite directions at a uniform angular velocity, and means for alternately connecting said gears with said member to move the latter first in one direction and then in the opposite direction at a uniform velocity, of a reversing mechanism including a second reciprocating member, one of said members having means adapted to be moved into engagement with the other member to connect them for movement together when the second member is reversing, and means for automatically operating said last mentioned means to move the latter to connect the two members substantially when one gear is disconnected from the first member and to disconnect the two members substantially when the other gear is connected with the said first member.

In testimony whereof I hereunto affix my signature.

WILLIAM M. KELLY.
